UNITED STATES PATENT OFFICE.

TEMISTOCLE E. MELA, OF SACRAMENTO, CALIFORNIA.

MAIL-BOX.

1,125,584.

Specification of Letters Patent. Patented Jan. 19, 1915.

Application filed February 10, 1914. Serial No. 817,748.

To all whom it may concern:

Be it known that I, TEMISTOCLE E. MELA, a citizen of the United States, residing at Sacramento, in the county of Sacramento and State of California, have invented certain new and useful Improvements in Mail-Boxes; and I do declare the following to be a clear, full, and exact description of the same, reference being had to the accompanying drawings and specifications.

This invention, which in its general nature relates to improvements in mail boxes used by the Government in the collection of mail matter, has more particular reference to certain details of improvement over that form of mail box shown in my Letters Patent dated May 27th, 1913, and numbered 1,062,785. The particular features improved upon are as follows, namely; first, an improved lock and operating connections between the lock and the gravity controlled bottom door and collection time indicator, and second, an automatic block or obstacle for the lock and its operating connections whereby the same cannot be operated or moved until the mail receiving pouch or sack is inserted beneath the box ready to catch the mail matter.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a front elevation of the complete device showing the mail receiving pouch in position thereon. Fig. 2 is a side elevation of the same. Fig. 3 is a sectional view taken on a line Y—Y of Fig. 2, showing the cover plate on the operating mechanism removed and also the lock housing removed. Fig. 4 is a sectional view through a portion of the box showing the operating mechanism in side elevation. Fig. 5 is a rear elevation of the lock showing the automatic block in position to prevent operation and with the rear side of the lock housing removed and the keeper partly broken out and in section. Fig. 6 is a side elevation of the same. Fig. 7 is a detailed view of the upper portion of the mail receiving pouch shown

in open position. Fig. 8 is a similar view showing the same in closed position. Fig. 9 is a front elevation of the time of collection indicator. Fig. 10 is a sectional view taken on a line X—X of Fig. 9.

Referring now more particularly to the characters of reference on the drawings, the numeral 1 designates the main body of the box which is, in my improved structure, provided with an auxiliary forwardly projecting casing 2 adapted to receive the operating mechanism, which casing 2 is suitably separated from the main body 1 by means of a removable plate 3 to prevent the mail matter getting into contact with the operating means which might prevent successful operation. At the bottom of the box 1 and at each side thereof is a slotted guide 4 adapted to receive flanged side bars 5 secured to each side of the mail receiving pouch 6 to bring such pouch 6, when in open position, directly under the mail box. Said mail box has a hinged bottom 7 adapted to drop open in such a manner as to hang from the rear edge of the box to facilitate the ready discharge of the mail matter into the receiving pouch. Such door 7 is normally locked in closed position by means of a catch 8 engaging a slidable spring controlled keeper 9, the movement of which keeper is actuated by the lock, which lock consists of a key receiving rocking pin 10 suitably journaled in the lock housing 11 and projecting at its forward end through the member 2 to allow of the insertion of the key which may be of any desired form. On said member 10 is secured a projecting arm 12 adapted to move with the rocking movement of said pin 10 and held in normal position by a helical spring 13 secured thereto, as at 13^a, and then extending around the member 10 and projecting to an independent point, as at 13^b, where it is again fastened.

With the rotary motion of the member 10, the arm 12 moves over the surface of an inclined cam 14 secured on the face of a depending plate 15 which is swung by pins 16 in the ends of the lock housing 11. The lower edge of the member 15 is provided with lugs 17 which fit into recesses 18 in the upper face of the keeper 9 so that with the movement of the arm 12 against the cam 14, the plate 15 will be swung on its pivotal connections 16 causing the lugs 17 to move the keeper 9 out of engagement with the catch 8 which then releases the bottom 7 to

permit it to drop open, which rotary motion is imparted to the member 10 by the inserting and turning of a key therein from the outside of the mail box. This rotary motion however is blocked against operation until such time as the mail pouch is in a position to receive the mail by means of the following structure, namely: A projecting obstacle 19 engages the upper end of the member 12 to normally prevent its movement, which member 19 is suitably secured to a pin 20 suitably journaled in the side of the mail box 1 at one end and in a bracket 21 secured to the lock housing 11 at the other end. On one end of said pin 20 is a depending lug 22 which projects into the path of one edge of the mail pouch when the same is inserted in position in the guides 4. The normal position of the obstacle 19 is maintained by a spring 19^a, and as has been stated, the normal blocking position of such obstacle 19 obstructs the movement of the member 12, but when the mail pouch is inserted into position, it engages the lug 22 and rotates the pin 20 and moves the member 19 out of the path of the member 12 and permits it to be operated in the manner described to empty the mail matter into the pouch which is always in inserted position ready to receive the same before the bottom drops open.

Simultaneously with the delivery of the mail into the pouch in the manner above set forth, I provide a means for opening the normal closure covering for the time of collection indicator, which cover is designated by the numeral 23, which is hinged at its lower end as at 24 and held in normal closed position at its upper end by means of a catch 25 which normally engages a recess 26 in the upper edge of the member 23. Said catch has a projecting arm 27 pivotally mounted as at 28. Said arm 27 is connected with the arm 12 by means of links 29 and 30, such link 30 having springs 31 and 32 each being disposed on one side of the arm 27 to maintain its normal position and to maintain the catch in its engaged position with the recess 26 whenever the cover 23 is closed. By means of the above structure, whenever the arm 12 is moved to open the door 7, the catch 25 is disengaged from the recesses 26 and the cover 23 then drops open by gravity leaving the indicator free to be set at such point as is necessary to designate the hour at which the next collection may be made. The indicator comprises a disk 33 on which is indicated the hours, two pointers 34 which move over the face of such disk 33, and a sector 35 containing the designations A. M. and P. M. adapted to be exposed as desired through a slot 36 in the disk 33. The members 33, 34 and 35 are all held in position in frictional contact with each other by means of a thumb screw 37 which screws

into the body of the member 2 as seen in Fig. 10.

The mail box may be secured to the supporting post by means of screws or bolts 38, the heads of which are countersunk into the inside of the box as shown clearly in Fig. 4, which bolts may be inserted into position by any suitable tool made for the purpose whereby the inside surface of the box may be uninterrupted to allow of the free passage of the mail matter.

Reviewing now briefly the complete operation of the device, the mail collector opens his pouch into the position shown in Fig. 7 and then inserts the members 5 into the guides 4. With this insertion the lug 22 is moved to operate the pin 20 to remove the obstacle 19 from the path of the arm 12. The collector then inserts his key in the member 10 and rotates said member 10, the limit of rotation being determined by spaced pins 12^a and 12^b on the cam 14 adapted to be engaged by the arm 12. This rotation of the member 10 moves the arm 12 against the cam 14 causing the plate 15 to move the keeper 9 away from the catch 8 and allowing the door 7 to drop down delivering the mail into the pouch. Simultaneously the downward movement of the arm 12 pulls on the links 29 and 30 and releases the catch 25 and the cover 23 drops open in the manner described. The collector then sets the time for the next collection and rotates the member 10 back to normal position, closes the cover 23, removes the pouch 6 and the obstacle 19 is then forced into the path of the arm 12 by the spring 19^a and the door 7 is again closed engaging the catch 8 with the keeper 9 and the box is then ready for the receiving of further mail matter.

The hours of collection may be suitably shown on a plate 39 held in position on the front of the member 2 by means of a pivoted bar 40 engaging hooks 41 within the member 2. The mail pouch 6 has a clasp 42 to engage the end bars 43 to hold the same closed.

From the foregoing description it will readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention what I claim as new and useful and desire to secure by Letters Patent is:—

1. In a mail box having a discharge outlet and a locked closure for its discharge outlet and an indicator and a locked cover for its indicator and a key controlled rotatable member for simultaneously releasing

both of said locks, of an arm on said rotatable member, an obstacle normally engaging said arm to prevent rotation of said rotatable member and means for removing 5 said obstacle under predetermined conditions, as described.

2. In a mail box having a discharge outlet and a locked closure for its discharge outlet and a bag receiving means adjacent 10 said closure, and a key controlled member for releasing said lock, an obstacle normally preventing operation of said key controlled member and means on said obstacle projecting adjacent said bag receiving means and 15 being operable to move said obstacle to allow of the operation of said key controlled member, as described.

3. In a mail box having a discharge outlet and a locked closure for its discharge outlet and a key controlled rotatable member 20 for releasing said lock, an arm on said rotatable member, an obstacle normally engaging said arm to prevent rotation of said rotatable member, a rotatable pin secured to said obstacle, and a lug secured to said rotatable pin and projecting outside of said mail box.

In testimony whereof I affix my signature in presence of two witnesses.

TEMISTOCLE E. MELA.
